PITCHING HORSESHOE

Clyde W. Martz, 3233 Arapahoe Road,
Pittsburgh, Pa. 15234

Filed Jan. 31, 1967, Ser. No. 5,638

Term of patent 14 years

(Cl. D34—5)

FIG. 1 is a perspective view of a pitching horseshoe showing my new design.

FIG. 2 is plan view of the pitching horseshoe illustrated in FIG. 1.

The characteristic feature of my design resides in the particular stepped configuration at the open ends or heel portion.

I claim:

The ornamental design for a pitching horseshoe, as shown and described.
